UNITED STATES PATENT OFFICE.

IRWIN A. SEIDERS, OF PENNSIDE, PENNSYLVANIA.

DESIGN FOR A CYLINDER-COCK CASING.

55,436.

Specification for Design.

Patented June 8, 1920.

Application filed December 3, 1919. Serial No. 342,273. Term of patent 7 years.

To all whom it may concern:

Be it known that I, IRWIN A. SEIDERS, a citizen of the United States, residing at Pennside, in the county of Berks and State of Pennsylvania, have invented a new, original, and ornamental Design for a Cylinder-Cock Casing, of which the following is a specification, reference being had to the accompanying drawing, forming a part thereof.

In the drawing:—

Figure 1 is a side elevational view of my design.

Fig. 2 is a like view, taken at right angles to the view disclosed in Fig. 1.

Fig. 3 is a plan view thereof, showing the under side of the design.

I claim:—

The ornamental design for a cylinder cock casing, as shown.
